ART OF DRILLING DEEP WELLS

George L. Ratcliffe, Los Angeles, Calif., assignor
to National Lead Company, Los Angeles, Calif.,
a corporation of New Jersey

Application December 19, 1938, Serial No. 246,618

4 Claims. (Cl. 255—1)

This invention relates to the art of drilling deep wells and more particularly to the drilling of such wells through shale formations.

In the procedure of drilling deep wells such as oil and gas wells the rotary drilling procedure is employed. In such a procedure a drilling fluid is used which is introduced through the drill stem to the bit and there issues to rise in the bore hole; from hence it is conducted to a settling ditch where the cuttings are settled out, and then to a suction pit, from which the fluid is again conducted into the drill stem. In some instances the cuttings are separated from the drilling fluid by screens.

The drilling fluid performs various functions such as carrying the cuttings to the top of the well, but a particularly useful function of the drilling fluid is to wall the bore hole. Accordingly, the fluid should contain a wall-building component which, where ordinary clay is used, is the clay itself, including its gel-forming component. In many instances a concentrated colloidal clay such as bentonite is employed, as disclosed in the Harth Patent No. 1,991,637, patented February 19, 1935. In some instances a mud weighting material is employed, as disclosed in the Stroud Patent No. 1,575,945, patented March 9, 1926.

When a drilling mud consisting of water and clay comes in contact with a bed of shale as the well is drilled, a certain amount of water from the drilling mud seeps into the shale and wets it to a depth of one-fourth inch or so. The action of the water varies on different shales inasmuch as some shales chip off in small flakes when the surface becomes wet to a depth of one-eighth or one-fourth of an inch; some shales become wet and sticky and do not slough off and still other shales disintegrate rapidly to a powdered form when they become wet.

Applicant has found that if the wetted portion of shale together with any filter cake which may have been formed on the face of the shale by the drilling mud is placed under considerable pressure, the wetted portion will be consolidated by the pressure into a hard, compact, impervious mass. The higher the pressure placed upon the shale, the more compact will this sheath upon the face of the shale become.

One of the objects of this invention is to provide a process having for its purpose preventing of sloughing, caving or heaving of shales ordinarily encountered in oil well drilling; and in accordance with this invention this is accomplished by applying sufficient pressure to the wet

shale to insure consolidation of the wetted portion into a firm, compact mass which not only prevents water infiltration but also mechanically strengthens the wall of the bore hole.

Another object of this invention is to provide a process in which the drilling fluid containing a wall-building component is subjected to a pressure sufficient to compact the wall-building component on the wall of the well.

Further objects will appear from the detailed description taken in connection with the accompanying drawings showing illustrative embodiments of this invention, although it will be understood that this invention is susceptible of various embodiments.

As set forth above, some shales tend to cave or slough more readily than other shales and it is, therefore, difficult to state exactly what pressure will be required to produce the desired result inasmuch as obviously it would be necessary to compact a badly caving shale more than it would be necessary to compact a shale which had only a tendency to cave or slough to a slight degree when wet. Generally speaking, however, ordinary clay drilling fluids have not been able to prevent the type of heaving or sloughing to which reference has been made. The ordinary clay drilling fluid, made up of clay and water only, would weigh say seventy-five pounds per cubic foot or would have a specific gravity of approximately 1.2. The maximum weight of fluid which can be made up out of clay and water and still be utilized in drilling, is ninety pounds or less. Such a fluid would have a specific gravity of 1.44. An average drilling fluid, therefore, let us say would have a specific gravity of 1.32. If a shale were encountered at the bottom of a well 5,000 feet deep in which a mud fluid having a specific gravity of 1.32 was being used, it would have a pressure on it, due to the weight of the mud column, of 2,864 pounds per square inch; under the same conditions, a shale encountered at a depth of 10,000 feet would have a hydrostatic pressure on it, due to the weight of the mud column, of 5,738 pounds per square inch. These figures are based on the assumption that no pressure exists in the shale itself. Generally speaking, these pressures are not sufficient to prevent the caving or sloughing to which reference has been made.

Greater pressures than those mentioned above, however, will compact shale to the point where caving, sloughing and heaving are prevented. Sometimes it is only necessary to slightly increase the pressure above this point but generally

speaking, it is safer to have a substantial margin of safety by increasing the pressure substantially above those pressures mentioned above. Applicant has found that this caving or sloughing will be prevented in the ordinary cases if the pressure is raised to a point where the pressure on the shale, expressed in pounds per square inch, is 75/100 times the depth of the hole in feet. Occasionally this pressure is not adequate and it is necessary to go higher than this. In some cases it will be advisable to have the pressure on the shale, expressed in pounds per square inch, equivalent numerically to the depth from the surface of the ground down to the shale in feet. In other words, in a hole 10,000 feet deep, it might be necessary to have a pressure on the shale at the bottom of the hole of 10,000 pounds per square inch in order to satisfactorily consolidate the shale and prevent heaving or caving. Possibly, even greater pressures might have to be resorted to under certain conditions.

These increased pressures are sometimes obtained by adding weight material (consisting of finely pulverized barytes, etc.) to the drilling mud so as to increase the weight of each unit volume of the mud thereby increasing the hydrostatic pressure. Applicant proposes to accomplish this by adding pressure to the drilling fluid over and above that due to the weight of the fluid itself so as to increase the pressure on the shale to the desired point. Applicant proposes to accomplish this in two ways:

First: By utilizing mud pumps which are capable of circulating the mud fluid at high pressures, or

Second: By utilizing a hydraulic pump at periodical intervals to increase the pressure on the drilling fluid and thus compact the shale.

In the first embodiment of applicant's invention, if it were desired to maintain a pressure of 10,000 pounds per square inch at the bottom of the 10,000 foot hole and the pressure on the shale due to the weight of the drilling fluid was 5,000 pounds per square inch, applicant would utilize slush pumps for circulating the mud which were capable of pumping the mud at a pressure of 5,000 pounds per square inch. This 5,000 pounds per square inch added to the 5,000 pounds per square inch due to the weight of the drilling mud column would provide the required 10,000 pounds per square inch at the bottom of the hole after its surface became wetted. In this embodiment a suitable back pressure on the mud discharged from the hole would be retained so the desired purpose would be accomplished.

Practically all deep wells drilled today are equipped with suitable blow-out preventers which can be closed against the drill pipe in order to hold any pressure encountered during drilling. These blow-out preventers are, customarily, only used when there is danger of a well blowing but due to high oil, gas or water pressures encountered in drilling. In the second embodiment of my invention the well would be drilled in the ordinary manner with regular drilling fluid which could consist of a straight clay drilling fluid or a clay drilling fluid weighted with barytes, iron oxide, or some other weighting material. When shale which is liable to cave or slough is encountered, it would be drilled in the ordinary manner for a given length of time or until a given amount of shale had been drilled. For example, say thirty feet of shale had been drilled, circulation of the mud fluid would be discontinued and a valve placed on the top of

the drill pipe and closed. The blow-out preventer would be closed packing off the space between the casing or the wall of the hole and the drill pipe. The hole would remain full of drilling mud. Pressure would then be placed upon the column of drilling mud through a pipe inlet to the casing below the blow-out preventer. By means of a hydraulic pump, water or additional drilling mud could be pumped in on top of the drilling mud in the well by the hydraulic pump until the pressure was raised to any desired point. The hydraulic pump could either be hand operated or driven in any customary manner. Care would have to be exercised not to use any more pressure than necessary due to the strain on the surface casing or other casing in the well and, of course, the pressure would have to be kept below a point at which the casing would be ruptured or the blow-out preventer cease to function. The desired pressure would be maintained for a suitable length of time, say a period of fifteen minutes or a half hour, until the pressure had compacted the wetted portion of the shale. The pressure would then be released and drilling would be resumed in the customary manner until enough additional hole had been made to render it advisable to compact the newly drilled shale before proceeding further. Experience would be the only guide as to the pressure necessary in any given case and as to the length of time it would be necessary to maintain the pressure in order to properly compact the newly wetted shale.

Pressure drilling methods are in use now but generally speaking they do not maintain more than 2,000 pounds excess pressure on the mud. Pressure drilling is not used at present to consolidate the shales but only for the purpose of confining oil, gas and water to their respective formations. In other words, the pressure drilling process is used to eliminate the necessity for weighted mud.

While the apparatus which may be used for performing the process may be varied, for illustrative purposes, two embodiments of apparatus which may be employed are shown in the accompanying drawings.

Figure 1 is an elevation partly in section illustrating an apparatus capable of carrying out the process embodying this invention; and

Figure 2 shows another form of apparatus.

In the drawings, Figure 1 shows an oil-well rig of conventional rotary type, equipped to drill under continuous high pressure according to the disclosure of this invention, and Figure 2 represents the same equipped to drill under usual conditions with the application of intermittent high pressures. It will be evident that a single rig can be fitted out to combine the features of both methods, to be used interchangeably as desired; but for clarity separate figures are used.

In either figure, 1 represents an intake of mud from the mud sump pit 2 to the pump or pumps 3. The output of 3 during drilling is passed through pipe 4 to the standpipe 5, thence through the hose 6, through a swivel 7 and down the kelly 8. The kelly is continuous with the drill pipe 9; the mud flowing downwardly therethrough passes through holes in the bit 10, up around the outside of the drill pipe into the flow line 11, thence through a ditch 12 back into the pit 2. 13 is the casing head, 14 a blowout preventer of usual design, its function being to pack off around the drill pipe, 15 a master gate valve, 16 a rotary table for imparting rotary motion to

the kelly and hence also to the bit. 17 is a draw works to operate the rotary table and operate the hoists.

Referring to Figure 1, special features enabling the continuous high pressure method to be carried out may be seen to be as follows: The compounding of the pumps 3, 18 and 19 enables high mud pressures of 5,000 to 10,000 lbs. per sq. in. to be produced. 20 is a pressure gauge indicating the pressure produced thereby. 21 is a packer around a kelly, a known and frequently used device to permit maintenance of pressure in the bore hole by preventing the escape of mud from the casing. This pressure is also maintained by a choke 22 in the flow line. If for example the hole is being drilled with 6,000 lbs./sq. in. applied mud pressure, there will be approximately this pressure differential across both kelly packer and choke. A float valve 23 is installed at the lower end of the drill string in order that new lengths of drill stem may be added while maintaining pressure in the well. During such an operation the blowout preventer is closed around the drill stem.

Referring to Figure 2, it will be seen that a three-way valve is installed at 24, in order that mud may be pumped either to the standpipe for routine drilling or through the feeder line 25 to the hydraulic booster 26, this last being a device enabling mud under very high pressure to be pumped into the space between drill pipe and casing at point 27, below the blowout preventer. A pressure gauge 28 indicates the applied pressure. In carrying out the process of the second method of the invention, drilling is interrupted, the blowout preventer is closed, valve 24 is turned so that mud will be fed to the booster, a valve 29 at the foot of the standpipe is closed, and mud is pumped into the casing at 27 under any desired high pressure, usually above 5000 lbs./sq. in. A float valve 30 is used here also to assist valve 24 in preventing mud issuing from the drill pipe.

It is desirable to keep both the continuous and intermittent pressures greater than the prevailing rock pressures, as thus caving from pressure release is prevented if the pressure is lowered below the rock pressure. The pressure employed is preferably at about one pound per square inch per foot of well depth. It has been found that in order to prevent ingress of water into heaving shale, intermittent pressure should be used for short periods of about two minutes and repeated every half hour. Furthermore, it is desirable to include a check valve just above the bit in the drill pipe to retain pressure in the hole when breaking the kelly or when applying pressure to the mud in the casing. Snubbers may also be necessary to force the drill pipe into the hole against pressure or maintain it there when pressure is momentarily reduced. In the event of a high sand content in the mud issuing from the bore, it may be necessary to carry out a partial desanding under pressure before passing the

mud through the final chokes so as to prevent clogging and undue wear of the chokes. An entirely closed mud system can also be used.

It will be seen that the invention accomplishes its objects. A process is provided in which sloughing, caving or heaving of shales ordinarily encountered in oil well drilling is not only prevented, but the wet shale is compacted to insure consolidation of the wetted portion into a firm, compact mass which not only prevents water infiltration but also mechanically strengthens the wall of the bore hole. This can be accomplished in a simple and effective manner and with a minimum of equipment. It is, of course, to be understood that this invention is applicable not only to rotary drilling, but to cable tool drilling. It is also applicable to situations where mud weighting and mud conditioning materials are employed.

It will be understood that not only is this invention susceptible of various embodiments, but that various changes may be made in details without departing from the spirit of this invention. It is, therefore, to be understood that this invention is not to be limited to the details described and/or shown.

Having thus described the invention, what is claimed is:

1. In the art of drilling deep wells through shale formations, the process comprising, employing a drilling fluid and subjecting the fluid repeatedly for short intervals to a pressure sufficient to insure consolidation of the wetted portion of the shale formation into a firm compact mass.
2. In the art of drilling deep wells through shale formations, the process comprising, employing a drilling fluid and subjecting the fluid to a pressure which at any depth is substantially in excess of that generated by the weight of the column of fluid at that depth in order to insure consolidation of the wetted portion of the shale formation into a firm compact mass.
3. In the art of drilling deep wells through shale formations with the aid of a drilling fluid, the process comprising, wetting the shale wall to a slight depth by means of the drilling fluid, and compacting the drilled shale formation where it has been wetted by applying thereto fluid pressure substantially in excess of the natural formation pressure whereby to consolidate said wetted portion into a firm, compact mass relatively impervious to water.
4. In the art of drilling deep wells through shale formations with the aid of a drilling fluid, the process comprising, compacting the drilled shale formation where it has been wetted by the drilling fluid by applying thereto repeatedly for short intervals, through the agency of the drilling fluid, fluid pressure substantially in excess of the natural formation pressure whereby to consolidate said wetted portion into a firm, compact mass relatively impervious to water.

GEORGE L. RATCLIFFE.
